CIRCUIT CONTROL DEVICE

Walter Clyde Austin, Burbank, and Webster Hill,
Los Angeles, Calif.

Application August 15, 1938, Serial No. 224,880

4 Claims. (Cl. 200—34)

This invention relates to a circuit controlling device, and more specifically to that type of device used for the time control of electric circuits.

An object of the invention is to provide an improved control means capable of making or disrupting a circuit after a predetermined interval has elapsed.

A further object of the invention is concerned with an improved device capable of controlling a circuit over a predetermined interval of time, and in which said interval can be varied.

Still another object of the invention involves the provision of an improved device for controlling a circuit in dependence upon the escape of an entrapped fluid from the device.

Another object is to provide a time control circuit device that is free from complexity and economical to manufacture.

Other objects and advantages of the invention will become apparent from the following description when taken in conjunction with the drawing, in which:

Fig. 1 is a diagrammatic view, illustrating one application of the invention;

Fig. 2 is a perspective view of the time controlled circuit device;

Fig. 3 is a longitudinal section of the device;

Fig. 4 is an end elevation of the device, as seen from the right of Fig. 3; and

Fig. 5 is a diagrammatic view, showing another application of the invention.

In the specific form of the invention disclosed in the drawing, it is desired to control the flow of current through an electric circuit. In furtherance of this objective, a lead 10 can have its end portion 11 fitting within a binding post 12 secured to a cover or end plate 13 for a cylinder 14. The cover is made of insulating material and carries a leaf spring contact 15 adapted to complete or disrupt the circuit by making or breaking contact with the flange 12a on the binding post. The insulated cover is secured to a flange 14a on the end of the cylinder by means of the screws 16 threadedly received in tapped holes 17 in the flange. One of these screws can serve as an anchor for the leaf spring, which has an extended portion 15a for receiving a second lead 16a for conducting current to or from a circuit controlled mechanism (shown in Figs. 1 and 5).

Engagement between the leaf spring 15 and the binding post flange 12a is controlled by a timing mechanism, part of which is contained within the cylinder and part outside of the insulated cover plate. The portion within the cylinder includes a piston 18 consisting preferably of a cup-

shaped packing 18a fastened to a piston rod 19 by means of the opposed plates 18b, 18b and opposed nuts 18c, 18c, threadedly received on the end portion of the rod. The other end of the rod is also threaded, carrying a knurled nut 20 and also a lock nut 21 to hold the nut 20 securely on the rod in various positions of adjustment; wherefore the time control of the circuit can be varied, in a manner to be hereinafter explained.

The piston rod 19 extends through the leaf contact spring 15 in order that inward positioning of the circuit breaking nuts 20, 21 can move it away from the binding post flange 12a. Such inward positioning is obtained under the influence of a return helical spring 22 abutting at one end against the piston and at its other end against the insulated cylinder end plate 13. It will therefore be apparent that the spring will normally urge the piston and the circuit breaking nuts on the end of the rod inwardly, as shown in Fig. 3; but that outward movement of the knurled nut to the dotted line position will permit the leaf spring 15 to engage with the binding post 12 to complete the circuit, at the same time compressing the helical spring, which would immediately return the parts of the mechanism to their initial circuit breaking positions were it not for the provision of a time delay mechanism incorporated within a device.

To retard inward movement of the piston 18 and nuts 20, 21 on the end of the rod, the rod 19 is provided with a bore 19a extending entirely therethrough from the high pressure end of the piston to the threaded bore 20a in the knurled nut. As the piston and nut are retracted, air can flow past the cup-shaped packing 18a from the low pressure end of the cylinder to the high pressure end thereof. This is readily accomplished in view of the ease with which the cylinder contacting portions of the packing can collapse under the pressure of the air flowing in the manner indicated. However, as the helical spring tends to return the piston to its initial position, the air at the high pressure cylinder end will expand the packing against the cylinder walls preventing seepage therearound, the only path of air movement being through the hollow piston rod 19 and through the nuts 20, 21 to the atmosphere. For the purpose of restricting the flow of air, a small plate 23 is inserted in the bore of the knurled nut so that it will tend to snugly engage the end of the rod. In addition, delay in the escape of air is obtainable by the packing effect produced by the threaded connection between the nuts 20, 21 and the piston rod 19. It will be appreciated that

the air must pass through the piston rod and then around the undulated threads prior to its escape to the atmosphere. If the effects of the threads were to be minimized, ease of air escape could be 5 readily provided by forming a flat side 19b along one portion of the piston rod.

One application of the invention is disclosed in Fig. 1, in which a propeller 30 of a model aeroplane (not shown) is driven by a small internal combustion engine 31 that is supplied with fuel from a suitable source (not shown). Such aeroplanes are designed to operate over relatively short intervals of time, their period of flight presently being governed by the extent of the fuel supply. To definitely determine the flight time and to render it independent of the fuel supply, the circuit controlling device of the present invention can be incorporated in the ignition system of the internal combustion engine.

20 The controlling device is placed in series between a battery 32 and the usual coil or auto-transformer 33 used in ignition systems, with the usual make and break 34 interposed in the line for insuring the induction of a high voltage into 25 the secondary circuit of the coil, in which circuit is included the engine spark plug 35. A condenser 36 is connected across the make and break device for preventing arcing.

When flight of the aeroplane is desired, the 30 knurled nut 20 is grasped by the fingers and the piston and piston rod pulled with it outwardly against the action of the helical spring, permitting contact to be made between the leaf spring 15 and the binding post 12, current flowing 35 through the coil 33 as governed by the make and break 34 to induce a spark across the spark plug terminals. The compressed helical spring 22 will immediately urge the piston, rod and knurled nut towards circuit breaking position, but its influence will be delayed through the resistance offered by the relatively slow escape of air through 40 the piston rod and knurled nut. The nuts on the outside of the cylinder will therefore be moved inwardly very slowly, the engine being 45 operated until the leaf spring is moved from the binding post by its contact with the lock nut. The time of flight can readily be varied by threading 50 the knurled nut and lock nut on the rod to alter their positions thereon, and therefore, the distance that the rod must be returned by the helical spring before the leaf spring contact will be moved from the binding post.

Fig. 5 discloses a further mode of using the invention, as by incorporating it in series with an 55 incandescent light bulb 37, the current to the bulb being disrupted after a predetermined period of time, depending upon the setting of the leaf spring moving members 20, 21.

While the specific embodiment has been shown 60 applied to the breaking of a circuit after a predetermined time interval, it will be apparent that the control parts can be easily arranged so that the circuit will be completed after the passage of such interval, as by causing the leaf spring to 65 engage with the binding post upon inward engaging movement of the knurled nut and locked nut. It will also be appreciated that circuits other than electric ones can be controlled by the timing device, including valve mechanism, parking meters, paper towel dispensers, lawn sprinkler systems, etc.

It is to be understood that the specific embodiment disclosed on the drawing is merely illustrative of the invention, which is best defined in the appended claims.

We claim:

1. A circuit control device comprising a cylinder having a leaf spring switch secured thereto and insulated therefrom, a spring operated piston mounted in said cylinder, a fluid conveying hollow piston rod secured to said piston, said rod having its inlet end in fluid communication with the high pressure side of said cylinder and its outer fluid discharge end projecting from said cylinder, and valve means on the outer end of said rod for controlling the flow of fluid from the projecting discharge end of said rod and operating said switch on a retracted movement of the piston.

2. A circuit control device comprising a cylinder having a normally closed leaf spring switch mounted thereon and insulated therefrom, a spring operated piston mounted in said cylinder, a fluid conveying hollow piston rod secured to said piston and having its inlet end in fluid communication with the high pressure side of said cylinder and its outer discharge end projecting from said cylinder, and an adjustable nut on the outer end of said rod for controlling the flow of fluid from the projecting discharge end thereof and also for the operation of said switch on an inward movement of said piston.

3. A circuit control device comprising a cylinder closed at one end, a plate formed of an insulating material secured to the open end of said cylinder, a terminal binding post secured to said plate, a leaf spring terminal secured to said plate its free end normally out of engagement with said binding post, a piston mounted in said cylinder, a hollow piston rod secured to said piston and in communication with the high pressure side of said cylinder and having a flattened outer end portion projecting beyond said insulating plate, an expansion spring mounted in said cylinder between the piston and insulating plate for forcing the piston inwardly, and an adjusting nut threadingly engaging said piston rod for regulating the flow of fluid from said cylinder and for operating said leaf spring to open the circuit when said piston has been fully retracted.

4. A circuit control device comprising a cylinder closed at one end, a plate formed of an insulating material secured to the open end of said cylinder, a terminal binding post secured to said plate, a leaf spring terminal secured to said plate with its free end normally out of engagement with said binding post, a piston mounted in said cylinder, a hollow piston rod secured to said piston and in communication with the high pressure side of said cylinder and projecting beyond said insulating plate, an expansion spring mounted in said cylinder between the piston and insulating plate for forcing the piston inwardly, and an adjusting nut threadingly engaging said piston rod for regulating the flow of fluid from said cylinder and for operating said leaf spring to open the circuit when said piston has been fully retracted.
